US00D660491S

(12) **United States Design Patent**
Holscher

(10) **Patent No.:** **US D660,491 S**
(45) **Date of Patent:** **** May 22, 2012**

(54) **EMERGENCY LIGHTING FIXTURE**

(75) Inventor: **Steven G. Holscher**, Boling Springs, SC
(US)

(73) Assignee: **Hubbell Incorporated**, Shelton, CT
(US)

(**) Term: **14 Years**

(21) Appl. No.: **29/391,067**

(22) Filed: **May 3, 2011**

(51) **LOC (9) Cl.** **26-05**

(52) **U.S. Cl.** **D26/63; D26/83**

(58) **Field of Classification Search** **D26/61, D26/63, 74, 80, 81, 83-89; 362/147, 488, 362/490, 515, 20, 249.1, 249.07, 285, 287; D10/114.1**

(57) **CLAIM**

The ornamental design for an emergency lighting fixture, as shown and described.

DESCRIPTION

FIG. 1 is a top perspective view of the emergency lighting fixture of the invention;

FIG. 2 is a front view of the emergency lighting fixture of FIG. 1;

FIG. 3 is a right side view of the emergency lighting fixture of FIG. 1;

FIG. 4 is a rear side view of the emergency lighting fixture of FIG. 1;

FIG. 5 is a left side view of the emergency lighting fixture of FIG. 1;

FIG. 6 is a top view of the emergency lighting fixture of FIG. 1; and,

FIG. 7 is a bottom view of the emergency lighting fixture of FIG. 1.
